UNITED STATES PATENT OFFICE.

THOMAS H. WALKER, OF KANSAS CITY, MISSOURI, ASSIGNOR TO EARL G. SPANGLER.

PUMPING DEVICE.

Application filed February 28, 1927. Serial No. 171,464.

My invention relates to apparatus for producing and using power and particularly to the application to a prime mover of a vapor alternately advancing and retreating as released and absorbed by a liquid.

One of the principles upon which my invention is founded is well known though so far as I am aware it never before has been employed in the actuation of a prime mover. I suggest as an example of the principle the ability of a specific amount of water to absorb and hold in solution a chemical that upon expansion and vaporization would have a volume substantially several hundred times the volume of the water; the release of the vapor from the water occurring through the increasing of the temperature of the water, and the vapor being reabsorbed upon restoration of the original temperature of the water to leave a vacuum in the enclosed area into which the vapor was released. The principle is widely used, for example in refrigeration plants, where pressure is present but is not a primary objective in the functioning of the device.

My object is to provide means whereby said alternating phases may be employed to confer reciprocal movement on a piston, a problem involved being the provision of a piston able to respond to and transmit the impulses without detriment to the efficiency of the vapor, and susceptible to retraction upon retreat of the vapor.

I conceive that the utilization of the phenomena mentioned will enable me to produce and transmit energy at a relatively low cost for fuel and mechanical labor. An installation under my invention would comprise a small number of parts, and especially an extremely small number of moving parts and elements, whereby the problems of lubrication, replacement, and costs and labor of installation would be greatly simplified. I have particularly in mind the pumping of water in drainage, irrigation, or like enterprise, for which continuous operation over a considerable period, with a minimum of attention to equipment, is desirable. I represent my invention therefore in terms of application to the pumping of water, though it may be adapted to the moving of other fluids and to actuation of other elements.

I provide for the accomplishment of my object a device comprising in its preferred form a vessel holding a volatilizable element, means for releasing vapor from the

element, means for reducing the vapor, and a pump or engine housing having a liquid piston to which the expanded vapor is admitted and from which in turn the vapor is withdrawn. The piston is of a nature to refuse to absorb or otherwise affect, or be affected by, the vapor, and is preferably an oil of a suitable nature. The piston is projected through chambers in the housing against water in a cistern or sump of the housing and propels the water therefrom. Removal of the vapor from the pump housing, by reduction or otherwise, permits atmospheric pressure on the water at the source from which it is being drawn, to return the piston to normal position and to propel a fresh charge of water into the sump for discharge by the succeeding positive phase of operation by the device, suitable inlets and outlets, and valves, being provided.

The details of a specific application of the principles will be particularly described with reference to the drawings in which:

Fig. 1 is a perspective view of my device, two of the pump members being shown in vertical cross section.

Fig. 2 is a cross section of tank elements and a perspective view of the heating element.

Fig. 3 is a detail perspective of a valve member controlling delivery of cooling water to a tank.

Referring in detail to the drawings:

1 designates a boiler or vapor-producing chamber, of which three are provided for continuous operation in the particular service illustrated, the boilers or evaporators being formed arcuately for disposition in a circle, and shown as spaced. The boilers contain a liquid, for example water, in which a gas is held in absorption, for example ammonia. A heating means is provided, which in the particular instance and for illustration, comprises a gas burner 2 having a curved nozzle 3, and is positioned beneath the group of boilers and erected on a vertical arm 4 of a feed pipe 5 through which the heating medium 6 may be fed from a source not shown controlled by a valve 7 in the feed pipe. The burner is rotatable by suitable means at appropriate speed to provide the period and degree of heating desired. The means of rotation illustrated is the impingement of the emitted gas at a calculated angle, volume and velocity to repel the free

curved end of the burner. I may install a thermostat on or in each boiler and provide suitable means of engagement with the burner which under a predetermined degree 5 of temperature would cause the burner to depart from a boiler, or conversely would under a specific low point of temperature cause the burner to direct its flame on a boiler.

14 The boilers 1 are supported by suitable means, the means illustrated being their suspension by the vapor-conducting tubes 8, one for each boiler to which it has inlet, the means of introducing the vapor-producing 15 liquid to the boilers being shown as ports 9 in the tubes vertically above the boilers, sealable by caps 10.

16 The gas held by the liquid has a marked affinity for water, in my illustrated usage. 20 The power impulses are produced by the release of the gas from the water under temperature increases, and the creation of a vacuum by the reabsorption of the gas by the water to permit atmospheric pressure to confer the return stroke. It is therefore important that the gas be all returned to the water in the boilers so far as possible, so that the efficiency of the solution may continue unabated.

25 Small quantities of moisture may however be accidentally released or discharged with the gas from the solution in the boilers under abnormal temperature increases, which might be deposited in the tubes or 30 elsewhere in the system. Moisture so deposited might erratically influence the functioning of the device by absorbing gas. Provision is therefore made to capture any vagrant moisture, comprising dehydrating 35 chambers 11 interposed in the tubes 8 in which suitable moisture absorbent may be installed to gather moisture from the gas traveling through the tubes and hold the same. The captured moisture, which may 40 be saturated with the gas, may be removed from the system by suitable means, for example by by-passing the gas around the dehydrating chambers, by renewal of the absorbent, or by heating the chambers for dispersal of the moisture back to the boilers.

45 The boilers are shown as suspended from the tubes 8 which are supported by the engine or pump units 12, each boiler and tube serving one pump, and a tube discharging 50 the gas expanded into it from a boiler into a piston chamber member 13 of a pump unit.

55 A pump unit comprises the cylindrical piston chamber member 13, having a closed lower end 14 provided with a drain 15 controlled by a faucet 16, and an inlet 17 above tightly closable by a cap 18; and a pump barrel 19 in which the piston chamber member depends axially and by which it is supported. A partition 20 divides the pump barrel to provide a larger upper portion

constituting a pressure well or piston cylinder 21 and a smaller lower portion constituting a cistern or sump 22, the two being connected by a central aperture 23 in the partition. Annularly positioned over the 70 aperture and depending from the partition is a tube 24 the lower end of which is spaced from the bottom 25 of the barrel and sump.

75 Inlets 26 are provided in the walls of the sumps adjacent the bottom thereof and the inlet pipes 27 connected to a main 28 that conduct water from the source of pumping operations into the sumps, the pipes having valves 29 closed under pressure from the 80 sumps.

85 Outlets 30 are provided positioned above the inlets, and having discharge pipes 31 connected to a discharge main 32 and having valves 33 opened under pressure from the 85 sumps.

90 The pressure well or upper part of a pump barrel into which a piston chamber member depends is upwardly closed by an annular horizontal wall 34, joining the top of the barrel with the piston chamber member, so that the pressure well or piston cylinder 21 is a sealed chamber, having a lower controlled passage through the aperture 23 of the partition into the sump, and a normally closed inlet that will now be referred to in connection with details of structure 95 constituting an important feature of the invention, and of the preparation of the device for operation.

95 A plunger tube 35 is vertically positioned 100 within the piston chamber 13, its open lower end spaced from the bottom of the chamber and having an elbow 36 projected through the wall of the chamber member and connected with a vertical tubular inlet 37 that 105 is extended downwardly and let into the horizontal upper closing wall of the piston cylinder portion of the barrel. A capped extension 38 of the tubular inlet is provided for introducing a desired quantity of water 110 to the pump barrel, and for other purposes that will be disclosed.

115 To prepare the device for functioning, water inlet and discharge connections being made, and provision made for operation of the boilers, water is introduced into the pump barrel through the inlet extension 38 sufficient to produce a desired level in the piston cylinder, for example, approximately to two-thirds the height of the cylinder. 120 The water in the pump is designated 39. The amount of water in the cylinder or well at any time may be observed in the water level glass 40 shown as installed in the wall of the pump barrel.

125 Oil designated 41 is then introduced through the port 17 of the piston chamber, and it passes from this chamber upward through the plunger tube into the inlet tube 37 and so into the piston cylinder, where it 130

fills the annular space above the water in the cylinder. The structure is so designed that approach of the oil level to the top of the inlet extension 38 indicates the desired level of oil in the piston chamber.

The caps indicated are of course installed on the ports mentioned.

The oil body in a piston chamber constitutes part of the liquid piston of the device, other parts being in the plunger tube and the piston cylinder. The expanded vapor delivered through a tube from a boiler or evaporator bears against such body of oil, the pressure being transmitted through the plunger tube to the portion of the piston in the piston cylinder which bears against the water and forces it through the outlet and to close the valve 29.

I have provided an oil for the purpose mentioned, for which the gas vapor used has no affinity—for example, if the fluid pumped is water and the vapor used is ammonia, the oil installed would be a mineral oil.

The oil piston is displaced in the piston chamber substantially the length thereof, and depresses the water in the piston cylinder to an extent depending on the relative dimensions of the expansion chamber, plunger and cylinder. The water column is positioned on the barrel so that its lower arm is in the area of the cylinder constantly occupied by water, its upper arm being in the area constantly occupied by oil, under normal operation.

The propulsion of water having been described, the opposite phase will now be referred to.

The vapor or gas released by heat from a boiler is removed, and is recalled thereto in my illustrated usage, by the cooling of the liquid or solution in the boiler, so that the liquid will reabsorb the gas. A vacuum is created in the tube and piston chamber, and air pressure on the water in the inlet pipes causes opening of the valve, the admission of water into the sump and cylinder, and the propulsion of the liquid cylinder on a return course through the plunger tube and to substantially fill the piston chamber. The cooling of the solution is provided for by a water jet nozzle 42 delivering a spray, and a cooling element is provided for each tank or boiler, a jet nozzle being served through a pipe 43 connected with the sump of a pump unit.

The operation of a water jet is intermittent, since a boiler is to be cooled after each incident of being heated and discharging vapor to propel a piston. The cooling and reduction of the vapor must occur in regular steps with the heating and propulsion. I therefore connect a jet pipe 43 that serves a boiler, with the sump of a pump unit that is pumped by an adjacent boiler. A positive impulse conferred on the oil and water

in a pump barrel projects therefore a small quantity of cooling water through a pipe 43 onto the boiler from which the heating element has been withdrawn, and which has completed its positive phase of operation. 70 In the pipes 43 are double-faced valves 44 whereby the volume and period of flow of a cooling spray may be regulated, comprising the coupling 45 engageable with the pipe, the inner ring 46 producing the reduced opening 47 and constituting a valve seat, the gravity piston 48 loosely positioned in the coupling and the valve gates 49 and 50 on the stem 51, the upper gate 49 being threaded on the stem for adjustment purposes, the 75 gates oppositely and reciprocally closing the opening 47. Pressure from the sump causes water to pass the piston normally depressed by its weight, and also to move it in the coupling because the water that is present within the valve assembly has easy egress through the opening 46 which is provided of larger area than the total of the cross section of spacing of the piston from the coupling. 80 An amount of water having passed through the valve and through the nozzle suitable for the particular cooling task, the gate 50 seats on the ring 46. Reverse actuation results when pressure from the sump is withdrawn, 85 gravity and atmospheric pressure through 90 the nozzle permit the piston to fall, the gate 95 49 seats on the ring to close the pipe.

A function of the depending tube connecting the piston cylinder with the sump may be mentioned as to prevent air admitted 100 with water to the sump through inlet 26 from access to the cylinder, the outer walls of the tube trapping the air, that rises to the roof of the sump, and escapes through the discharge pipe. It is important that air 105 be restrained from admission to the piston cylinder, since air admitted thereto would rise through the water and the oil, and accumulate, displacing the water and oil from normal occupancy of the area within which 110 they function, and so reduce the efficiency of such functioning.

What I claim and desire to secure by Letters Patent is:—

1. In combination with a power generating device comprising a tank, a volatilizable element in said tank, means for releasing said element to exert pressure, and a cylinder for receiving the element, a liquid in said cylinder having no affinity for said gas, 115 a well member adapted to receive water, a tube for conducting said liquid into the upper portion of the well, an outlet for the water impelled by the liquid under pressure of the gas, and means for restoring 120 the liquid to pre-actuated position.

2. In combination with a plurality of pumps having liquid pistons, a plurality of boilers for holding an element containing a releasable vapor, means for releasing said 130

vapor, and means for conducting the vapor to the pistons, means for removing said vapor from said conducting means including water jet elements actuated by said piston to project water against said boilers serving other pistons.

3. In combination with a boiler, a vapor element in the boiler, and heating means causing the boiler to dispense the vapor, a pump element having a piston cylinder, a sump receiving a fluid being pumped and connected with said cylinder, the cylinder containing a portion of said fluid, an inlet and an outlet in the sump for the fluid being pumped, a liquid piston actuatable by said dispensed vapor and propelling the fluid into the sump, pipes conducting a portion of the fluid so propelled against the boiler to cool it and cause recall of the vapor, and valves controlling the direction of fluid flow in consonance with the actuation of the piston, atmospheric pressure returning fluid to the sump upon recall of the vapor.

4. In a device of the class described, a liquid piston and a sump through which water

may be received and discharged, means in the sump for restraining air admitted with water from access to the liquid piston, and means for actuating the piston.

5. The combination with a device for pumping water from a source subject to atmospheric pressure, the device utilizing the energy of an alternately released and condensed vapor and including a tank for containing the condensed vapor, a cylinder to receive the released vapor, and means for heating the tank to release the vapor, of a sump, a piston in said cylinder actuated by the released vapor to impel the water from the sump, and means for restoring the piston to pre-actuated position including a jet element for conducting a portion of the water from the sump to the tank to cool the same to condense the released vapor, atmospheric pressure delivering water to the sump from the source and returning the piston to preactuated position.

In testimony whereof I affix my signature.

THOMAS H. WALKER.
